U.S. Appl. No. 29/447,926, filed Mar. 7, 2013; Daniel Yonil Jung.

Primary Examiner — Wan Laymon(74) *Attorney, Agent, or Firm* — Thorpe North & Western LLP(57) **CLAIM**

The ornamental design for the dental handpiece, as shown and described.

DESCRIPTION

FIG. 1 is a perspective view of the dental handpiece in accordance with my invention with orbs thereon;

FIG. 2 is another perspective view thereof;

FIG. 3 is a top plan view thereof;

FIG. 4 is a right side elevation view thereof;

FIG. 5 is a left side elevation view thereof;

FIG. 6 is a bottom plan view thereof;

FIG. 7 is a front elevation view thereof; and

FIG. 8 is a rear elevation view thereof;

FIG. 9 is a perspective view of another embodiment of the dental handpiece in accordance with my invention;

FIG. 10 is another perspective view thereof;

FIG. 11 is a top plan view thereof;

FIG. 12 is a right side elevation view thereof;

FIG. 13 is a left side elevation view thereof;

FIG. 14 is a bottom plan view thereof;

FIG. 15 is a front elevation view thereof; and,

FIG. 16 is a rear elevation view thereof.

The broken lines in FIGS. 1–16 are for illustrative purposes only and form no part of the claimed design.
